UNITED STATES PATENT OFFICE.

HORACE S. CARLEY, OF BOSTON, MASSACHUSETTS.

LIFE-BOAT.

SPECIFICATION forming part of Letters Patent No. 627,979, dated July 4, 1899.

Application filed April 22, 1899. Serial No. 714,149. (No model.)

To all whom it may concern:

Be it known that I, HORACE S. CARLEY, a citizen of the United States of America, and a resident of Boston, Massachusetts, have invented a new and useful Improvement in Life-Boats, which invention is fully set forth in the following specification.

This invention has reference to life-boats, more particularly of a collapsible type adapted to be stored at convenient places on board of vessels or ships of all characters and at docks, wharves, or the like and to be used only in case of emergency, such as sinking of the vessel or other accident endangering the lives of people by drowning.

I am aware that it has heretofore been proposed to construct such a boat of an outer continuous buoyant frame in the middle of which is secured a collapsible or extensible bottom. When the life-boat is stored on a vessel or elsewhere, said bottom folds up within the outer buoyant frame; but when the boat is thrown overboard no matter which side of the buoyant frame strikes the water the collapsible bottom will drop through the frame and extend itself. Life-boats of this general character have not, however, so far as I am aware, met with practical success or been practically used, which I believe to be due to the fact that none of the constructions heretofore proposed have been capable of meeting the requirements of successful use.

It is the object of my present invention to provide a construction that will efficiently meet all of these requirements and prove a reliable and ever-ready means of saving the lives of people in the most turbulent seas.

Among the many requirements above referred to mention may be made of the following: The life-boat must be collapsible and when collapsed must be very compact, so as to occupy the least space possible on board of a ship, where space is always at a premium, and for the further reason that upon the space occupied by each life-boat when thus stored often depends the number of such boats carried by a vessel or ship, and consequently the completeness of its life-saving equipment. It must be capable of withstanding severe shocks and strains, as when thrown overboard it strikes the surface of the water with great force, and must withstand all kinds of weather.

Its efficiency must not be affected by non-usage, as boats of this character are often allowed to remain stored for long periods of time without even being tested. It must of course be reversible, so that it will right itself no matter which side strikes and rests in the water, and, further, it must be practically unsinkable and non-capsizable to its fullest capacity of accommodation to people who may get inside of or cling to it. It must, furthermore, be extremely durable and so simple in structure that novices may easily handle and manipulate the same.

The life-boat constructed in accordance with and embodying my present invention will, it is believed, meet all of the requirements of successful use and will be best understood by reference to the accompanying drawings, wherein—

Figure 1 is a perspective view showing the bottom of the boat extended. Fig. 2 is a perspective view in section through the buoyant ring. Fig. 3 is a plan, and Fig. 4 a section, of the flat part of the bottom. Fig. 5 is an enlarged sectional view through the buoyant ring, and Fig. 6 is a perspective sectional view showing the drag or ballast bag supported from the rings on the buoyant frame.

Referring to the drawings, A represents the buoyant frame or ring, consisting of an inner tube a, (or there may be a plurality of such tubes,) of suitable length, made, preferably, of a material such as rubber composition and filled with air either at or slightly above atmospheric pressure. About tube a are tightly packed layers of cork b, which not only contribute to the buoyancy of the ring, but protect the inner tube. A covering c, of canvas or similar material, is tightly bound around the cork, and to still further strengthen and protect the whole I prefer to completely cover the canvas with rope wound in convolutions thereabout.

The shell of the boat, or what may more properly be said to be the hull thereof, consists of a flexible part D, shown in the drawings as a net, which is preferred, although it may be of canvas or of some other such material impervious to water. Net D has along its upper edge a binding-rope d, to which are secured at suitable intervals cringles or eyelets d', through which pass rings d² of rope.

or metal, said rings fitting loosely about the buoyant ring A. At its lower edge net D is secured to the edge of a flat bottom part E, formed of two layers of canvas $e\ e$, (see Figs. 3 and 4,) fastened together along their edges, and between which are interposed cross-slats e^2 , of wood, connected by a longitudinal slat e' , which impart rigidity to bottom E.

A very important feature of the invention 10 is the marine drags or water-bags F F', each made of flexible fabric, such as canvas, attached along the open end of the bag to a hoop f^3 and connected, respectively, to opposite sides of flat bottom E by means of lines ff . 15 On the under side of each bag is attached a weight f' , which insures its sinking to the limit allowed by lines ff and filling with water. A string f^2 , running down inside of each bag F F' and secured at the bottom thereof, 20 enables the same to be turned inside out and drawn up against bottom E when not desired to be used. In Fig. 1 of the drawings the life-boat is shown extended to the form it takes when resting in the water, the bag F being 25 suspended from the under side thereof and the lines ff held taut. Bag F' in this figure is collapsed and rests against the upper side of the flat bottom E.

Of course in the event of the boat being 30 thrown into the water in a reversed position—that is to say, with what is the upper side in Fig. 1 down—then the bag F' would fill with water and bag F would rest in a collapsed condition against bottom E.

35 Instead of attaching the bags F F' to the bottom E, I prefer to suspend them, as shown in Fig. 6, by means of four ropes f^4 , having eyelets at their upper ends engaging about four of the rings d^2 , respectively. In this 40 manner the pull of the bag is brought directly on the buoyant ring and the bottom E subjected to no strain whatever from this cause.

Around the outer edge of buoyant ring A runs a life-line H, attached at intervals in 45 eyelets h , through which rings d^2 pass. To line H are secured a number of auxiliary life-lines i, having thereon floats i' , which keep them on the surface of the water and within reach of a person in the water in the 50 vicinity of the boat. Around the inner edge of the frame A and hanging loosely between eyelets d' are two strips of fabric $k\ k$, one on each side of net D. Each span from eyelet to eyelet of that strip k which happens to be 55 within the net D when the boat is in the water forms a seat for one of the occupants of the boat.

When the life-boat herein described is not in use, it will of course be understood that it 60 is collapsed, the net D, bottom E, and bags F and F' being folded together within the buoyant ring A. When thrown overboard, no matter which side of the ring A strikes the water the bottom E will drop, and as the net 65 D becomes taut eyelets d' will slide along the rings d^2 to a position at or near the under side thereof, so that the pull due to the weight

of occupants of the boat will be (more or less) directly on the under side of the buoyant ring A. Unnecessary strains on the net, eyelets, and rings are thus prevented, and a shorter depth of netting may be used than if the edge of the net were fixed to the buoyant frame along a line around the inner edge thereof. At the same time that one of the bags F F' 70 which happens to be on the under side of the bottom E fills with water and sinks the length of lines ff . The sunken ballast or drag thus provided acts to balance and steady the boat and is an efficient protection against capsizing, particularly in rough weather and in the case of a cross-cut sea. When it is desired to 75 row or paddle the boat, the bag is turned inside out and drawn up against the bottom E by means of cord f^2 . 85

Having now fully described my invention, what I claim as new, and desire to secure by Letters Patent, is—

1. In a collapsible reversible life-boat, the combination with a buoyant body of annular or similar continuous form, of a flat bottom, a flexible part secured at one edge around the edge of said bottom, eyelets arranged at suitable intervals along the other edge of the flexible part, and rings on the buoyant body 90 passing through said eyelets and on which they are adapted to freely slide, the space within the buoyant body being entirely free from obstructions whereby the bottom and flexible part may drop through and depend 95 from either side thereof.

2. In a collapsible reversible life-boat, the combination with a buoyant body of annular or similar continuous form, of a collapsible body, secured to and adapted to depend from 105 either side of said buoyant body, and a bag suspended beneath said parts and adapted when filled with water to constitute a marine drag or ballast.

3. In a collapsible reversible life-boat, the combination with a buoyant body of annular or similar continuous form, of a collapsible body secured to and adapted to depend from either side of said buoyant body, a bag suspended beneath said parts and adapted when 115 filled with water to constitute a marine drag or ballast, and a line whereby said bag may be emptied and pulled up out of position for use.

4. In a collapsible reversible life-boat, the combination with a buoyant body of annular or similar continuous form, of a collapsible body secured to and adapted to depend from either side of said buoyant body, and two bags one connected on each side of the buoyant and collapsible parts and severally adapted when filled with water to constitute a marine drag or ballast. 125

5. In a collapsible reversible life-boat, the combination with a buoyant body of annular or similar continuous form, of a collapsible body having eyelets disposed at suitable intervals along its edge, rings on the buoyant body passing through said eyelets and on 130

which they freely slide, and two bags one on each side of the collapsible body connected to a suitable number of said rings by lines, and adapted when filled with water to constitute a marine drag or ballast.

5 6. In a life-boat of the kind described, the combination with a buoyant body of annular or similar continuous form consisting of an inner tube filled with air, layers of cork tightly packed around said air-tube, and a covering of canvas or similar material about said cork, of a collapsible body secured within said buoyant body and adapted to depend from either side thereof.

15 7. In a life-boat of the kind described, the combination with a buoyant body of annular or similar continuous form consisting of an inner tube filled with air, layers of cork tightly packed around said air-tube, and a covering 20 of canvas, and an outer covering of cord or

rope wound about the canvas, of a collapsible body secured within said buoyant body and adapted to depend from either side thereof.

8. In a life-boat of the kind described, the combination with a buoyant body of annular or similar continuous form, of a flexible part connected along one edge to the buoyant body and secured at its other edge to the edge of a flat bottom, said bottom consisting of two layers of canvas or similar material having interposed therebetween longitudinal and lateral stiffening-slats.

25 In testimony whereof I have signed this specification in the presence of two subscribing witnesses.
